The ornamental design for “handle for cleaning implement,” as shown and described.

DESCRIPTION

FIG. 1 is a perspective view of a “handle for cleaning implement” with the handle in a first position, incorporating the design;

FIG. 2 is a top view thereof;

FIG. 3 is a bottom view thereof;

FIG. 4 is a side view thereof;

FIG. 5 is another side view thereof;

FIG. 6 is a front view thereof;

FIG. 7 is a rear view thereof;

FIG. 8 is a perspective view of a “handle for cleaning implement” with the handle in a second position, incorporating the design;

FIG. 9 is a top view thereof;

FIG. 10 is a bottom view thereof;

FIG. 11 is a side view thereof;

FIG. 12 is another side view thereof;

FIG. 13 is a front view thereof;

FIG. 14 is a rear view thereof;

FIG. 15 is a perspective view showing a second embodiment of a “handle for cleaning implement” with the handle in the first position, incorporating the design;

FIG. 16 is a top view thereof;

FIG. 17 is a bottom view thereof;

FIG. 18 is a side view thereof;

FIG. 19 is another side view thereof;

FIG. 20 is a front view thereof;

FIG. 21 is a rear view thereof;
